UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 904,689.

Specification of Letters Patent.

Patented Nov. 24, 1908.

Application filed July 20, 1905. Serial No. 270,527.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more especially to tabulating mechanism for such machines.

My invention has for its principal object to provide an improved denominational 15 tabulator.

To this and other ends, my invention consists in certain features of construction and combinations and arrangements of parts which will be fully set forth herein and particularly pointed out in the claims.

In the accompanying drawings, Figure 1 is a right-hand side elevation of a typewriting machine having my invention applied thereto, parts of said machine being 25 broken away and parts shown in section. Fig. 2 is a top plan view of the key action of my tabulator, parts of the typewriting machine being shown in horizontal section. Fig. 3 is a rear elevation of the machine. 30 Fig. 4 is an isometric view of a part of the framework of the tabulator. Fig. 5 is an isometric view of the universal bar, forming part of the tabulator as seen from a point behind it.

35 I have shown my invention applied to a Monarch front-strike typewriter, but it will be obvious that said invention is applicable to other styles of typewriting machines. The base portion of the main frame of the 40 machine shown in the drawings, comprises side plates 1 connected together at their rear ends by a back plate 2 and a horizontal shelf 3. The side plates 1 are connected together just back of the keyboard by a transverse frame bar 4 and intermediate said frame bar 4 and the shelf 3 said side plates are connected together by a transverse frame bar 5. Posts 6 rising from said base portion of the main frame support a top plate 7. 45 Brackets 8 rising from said top plate support an upper rail 9 that is grooved in its lower face and a lower rail 10 that is grooved in its upper face. Said grooved rails coöperate with anti-friction balls or 50 rollers 11 to support a carriage 12 having

upper and lower grooves which coöperate with the balls or rollers 11. The carriage 12 is drawn across the machine by a spring drum 13 acting through a strap 14 which is connected at one end to said drum and at the other end to said carriage. The motion of said carriage is controlled by feed mechanism comprising a feed rack 14 which is supported on the rear ends of arms 15, the forward ends of which are rigidly secured to short shafts that are journaled in the end pieces of the carriage 12.

55 The rack bar 14 meshes with a pinion 16 carried by the forward end of a shaft which is journaled in a bracket or housing 17 mounted on the top plate 7. Said shaft at its rear end carries an escapement wheel 18 that is controlled by feed dogs 19 mounted on the upper end of an arm 20 forming part of a dog rocker that is pivoted in a bracket 21 depending from the top plate 7. Said dog rocker also comprises a forwardly extending arm 22 which is connected by a link 23 with an arm 24 connected to a universal bar 25. Said arm 24 and universal bar 25 form parts of a rock frame which also comprises a rock shaft 26 that is pivoted at its ends to the side plates 1. The universal bar 25 lies beneath a series of key levers 27, which at their rear ends fulcrum on a plate 28 and are provided at their forward ends with character keys 29. Each of the key levers 27 has pivoted thereto at 30 an upstanding sub-lever 31, the lower end of which projects below the key lever and is formed 35 with a slot which embraces a rod or abutment 32. At its upper end, each of the sub-levers 31 is connected by a link 33 with one of a series of type bars 34 which are pivotally mounted in any suitable manner in a type bar segment 35. The construction is such that when any character key 29 is depressed the upper end of the sub-lever pivoted thereto moves towards the back of the machine and the link 33 operates the corresponding type bar 34, causing one of the types 36 mounted thereon to strike against the front face of the platen 37, mounted on the carriage 12. At the same time the key lever depresses the universal bar 25, which, through the link 23, operates the dog rocker and permits the spring drum 13 to move the carriage a letter space distance towards the left. The free ends of the type bars 34 normally rest against a segmental pad 38 which 40 45 50 55 60 65 70 75 80 85 90 95 100 105 110

is supported from the type bar segment 35 by means of rods 39.

My tabulator mechanism comprises a tabulator bar 40 that is rigidly mounted at its ends on brackets 41 projecting toward the rear of the machine from the carriage 12. Said tabulator bar is formed on its front and rear faces with a series of vertical grooves or slots spaced a letter-space distance apart and one or more column stop pieces 42 are adapted to be mounted on said bar and retained in position by said vertical slots. As shown in Fig. 1, each of said column stop pieces is of inverted U-shape so that said stop piece may be slipped over the tabulator bar from the top, the legs of the stop piece fitting into one of the front slots and one of the rear slots respectively. Each of said stop pieces is formed with a rearwardly projecting lug or stop portion 43 which constitutes the column stop. Each of said column stops is adjustable transversely of the machine by removing the stop piece from the tabulator bar and inserting it in any one of the several pairs of front and rear slots corresponding to the different letter space positions of the carriage. In order to permit of the tabulator bar and the stop pieces moving with the carriage, the brackets 41 are arched toward the rear of the machine in the manner shown in Fig. 1, the tabulator bar lying between the arched bracket and the main body of the carriage.

The column stops 43 are adapted to cooperate with a series of denomination stops 44 which, as shown in the present instance, consist of the upper forwardly extending ends of a series of upright levers 45 which are pivoted intermediate their ends in a stationary framework adapted to be secured to the main frame of the typewriter. Said stationary framework comprises two upright posts 46 which are connected together at their upper ends by a transverse webbing 47 and near their lower ends by a cross piece or bar 48. The frame piece comprising the posts 46, web 47 and cross piece 48 may be and preferably is made of a single casting. The levers 45 are pivoted on a rod 49 that connects the two posts 46. Said posts are also connected at their upper ends by a plate 50 secured to the front faces of the forwardly extending ends of the posts. The plate 50 is formed with a series of slots a letter space distance apart and said slots serve as guides for the denomination stops 44. Each of the posts 46 has projecting from the lower end thereof a foot or bracket 51 which is secured by a screw 52 to the shelf 3. Said posts 46 extend up back of the top plate 7 and each of said posts has a bracket 53 projecting therefrom over said top plate. Each of said brackets 53 has a screw 54 passing therethrough and threaded into the top plate 7 so as to secure the

bracket to the top plate. Each of said brackets has threaded therethrough a set screw 55, the lower end of which engages the upper surface of the top plate 7. When the tabulator is attached to the machine the screws 52 are first tightened. The set screws 55 are then screwed down until they bear firmly on the top plate 7 and the screws 54 are then tightened. The tabulator frame is thus rigidly secured both to the shelf 3 and to the top plate 7 without the screws placing any strain on these parts of the main frame of the typewriter. Each of the levers 45 is curved towards the back of the machine where it passes the top plate 7 so that said lever shall not interfere with said top plate. The lower ends of the levers 45 play in fore and aft grooves formed in the upper surface of a cross bar 56, which is secured to the front face of the posts 46 just above the shelf or plate 3 by screws 57. Below the pivot rod 49 each of the levers 45 is formed on its rear edge with two lugs or nibs 58. One of these nibs has surrounding it one end of a compression spring 59, the rear end of which is seated in a hole in the cross bar 48 and presses against a screw 60 with which the rear end of said hole is plugged. As shown in Fig. 3 the screws 60 are staggered so that the springs 59 are connected with the upper lugs 58 on some of the levers 45 and with the lower lugs 58 on the others. A plate 61 lies across the rear face of the frame bar 48 and covers the ends of the screws 60. Said plate is secured to the frame by screws 62 (Fig. 1) that are threaded into holes 63 (Fig. 3) in the tabulator frame.

The denomination stops are operated by a series of tabulator keys 64 arranged in a transverse row in the keyboard of the machine back of the character keys 29. The tabulator keys 64 are mounted on the front ends of a series of levers 65, the rear ends of which are rigidly secured to a series of transverse horizontal rock shafts 66, which are pivoted in a frame 67 detachably secured to the main frame of the machine above the character key levers 27 and below the type bar system. The frame 67 has the outline best shown in Fig. 2. Said frame comprises two forwardly extending arms that lie over the frame bar 4 to which they are secured by screws 68. The rear side of the frame 67 is formed with a rearwardly projecting portion 69 that lies over the frame bar 5 to which it is secured by a screw 70. The forward ends of the key levers 65 are guided by slots in a comb plate 71 which is secured to the front face of the frame 67 by screws 72. The middle portion of the plate 71 is secured to a bracket 73 projecting toward the front of the machine from the frame 67. The upper part of said comb plate is bent toward the back of the machine and supports a pad or cushion 74 for arresting the keys in

normal position. In the present instance I have shown ten denominational stops 44 and ten keys 64, one key for each stop. The rearward extension 69 of the frame 67 is 5 made somewhat thicker than the remainder of said frame and this thicker portion extends in a V-shape toward the front of the machine, as shown in Fig. 2.

At about the center of the machine just 10 in front of the screw 70 a bracket or web 75 rises from the frame 67 and the inner ends of all but two of the rock shafts 66 are journaled in this bracket. The outer ends of said rock shafts are journaled on the reduced ends of pivot screws 76 which are threaded through ears or brackets 77 rising from the frame 67. I prefer to make the rock shafts 66 of different lengths as shown in Fig. 2, each one terminating directly 15 back of its corresponding tabulator key 64, so that the key levers 65 are mounted on the ends of the shafts. At appropriate points on the several shafts, arms 78 are mounted, each of said arms extending downward from 20 its rock shaft and entering one of a series of fore and aft slots 79 formed in the upper surface of the rearwardly extending portion 69 of the frame 67. Lying in said slots 79 are a series of push links or sliding bars 80 25 which extend toward the rear of the machine, passing between the sub-levers 31 and lying at their rear ends in the slots of the cross bar 56 which slots, as has been explained above, also serve to guide the lower 30 ends of the levers 45. The lower end of each of said levers is formed with a notch as shown in Fig. 1 and the lower end of each of the arms 78 is also formed with a notch so that the links 80 are prevented from being raised out of the slots in the plate 69 35 and cross bar 56. Each of the links 80, arms 78 and levers 45 is of such thickness as to move loosely in the guiding slots, but of such thickness that the arms 78 cannot pass 40 the end of the link 80 nor can the rear end of said link pass the lever 45. When any key 64 is depressed the corresponding rock shaft 66 is rocked and the arm 78 on said rock shaft pushes the link 80 towards the 45 rear of the machine and said link pushes the lower end of the lever 45 toward the rear of the machine, thus moving the upper stop end 44 of said lever forward into the path of the column stop 43. The parts are 50 returned to normal position by the returning springs 59.

As shown in Fig. 2 the left-hand one of the key levers 65 is connected to the rear-most of those rock shafts 66 which are on 55 the left-hand side of the bracket 75 and the arm 78 on this rock shaft cooperates with the left-hand one of the links 80. The second key 64 is mounted on the second rock shaft from the rear, said rock shaft standing in front of the rock shaft 66 and its arm

78 coöperating with the second link 80 and so on for the first five keys. The sixth and seventh keys have their rock shafts 66 lying in front of the bracket 75 and the right-hand ends of said rock shafts are journaled in an 70 ear or bracket 81 rising from the frame 67. The three remaining keys 64 have their levers 65 mounted on the right-hand ends of their rock shaft 66, the left-hand ends of which are journaled in the bracket 75, standing end to end to the first three rock shafts on the left-hand side. While this arrangement of the rock shafts and their coöperating parts has been described in detail it will, of course, be understood that it may be considerably varied.

Since the rock shafts 66 stand one in front of another, the levers 65 are of different lengths, those connected with the forward rock shafts being shorter than those connected with the rock shafts farther to the rear. In order to give the same extent of motion to the lower ends of the arms 78, the forward rock shafts lie on lower levels than the rear ones so that the arms 78 of said forward rock shafts are shorter than the corresponding arms of the rear rock shafts in proportion as the corresponding levers 65 are shorter. As will be seen in Fig. 1 the heights of the rock shafts vary regularly 95 so that the series of rock shafts is inclined from the front upward towards the back of the machine.

In order to release the carriage when any tabulator key is depressed, there is provided 100 a universal bar 82 which stands behind the series of levers 45 near their lower ends so that said universal bar is moved toward the back of the machine whenever any of said levers is operated by a key. The universal 105 bar 82 is carried by the upper ends of two arms 83 which have in their lower ends holes 84 which receive the reduced inner ends of pivot screws 85 which are threaded through 110 openings in ears or brackets 86, which project toward the front of the machine from the posts 46 of the stationary frame in which the levers 45 are mounted. Said universal bar is held in normal position by a compression spring 87 which at its forward end surrounds a lug 88 formed in the rear side of the universal bar 82 by cutting two notches in said universal bar, as shown in Fig. 5. The rear end of the spring 87 is supported 115 by a pin 88', projecting toward the front 120 of the machine from the plate 61. One of the arms 83 of the universal bar has projecting therefrom toward the front of the machine an arm 89 which, at its free end, carries a headed pin 90 that passes through 125 a slot in the lower end of a link 91, the upper end of which is pivoted to a lever 92 which in turn is pivoted on a shouldered and headed screw 93 threaded into a bracket 94 depending from the top plate 7. The lower 130

end of the link 91 consists of a piece 95 which is threaded onto the upper section of the link and in which is formed the slot that cooperates with the pin 90. The length of the link 91 may be regulated by adjusting this lower section 95, screwing it up or down on the upper section of the link. The free end of the lever 92 has pivoted thereto the stem of a rack lifter 96. Said stem passes loosely through a slot in the top plate 7 and the upper end of said rack lifter is forked to embrace the reduced forward end of the housing or bracket 17 that supports the escapement wheel shaft. The upper end of each of the forks of the rack lifter is bent toward the front of the machine and lies beneath the feed rack 14. The construction is such that whenever any tabulator key is depressed the universal bar 82 is moved toward the rear of the machine and the arm 89 lifts the link 91, which, through the lever 92, elevates the rack lifter 96 which raises the feed rack 14 out of engagement with the feed pinion 16. I prefer to so adjust the lower section 95 of the link 91 that the pin 90 does not normally stand at the upper end of the slot in said lower section of the link but stands a little below the upper end of said slot as shown in Fig. 1 so as to provide a suitable amount of lost motion between the rack lifter and the tabulator key to insure that the carriage shall not be released before the tabulator stop is in position to arrest it.

I prefer to so space the slots 79 in the frame 67 that each of said slots stands directly in front of the space between two of the sub-levers 31. This space in the present instance is a little wider than the distance between the levers 45, and the rear ends of the links 80 are accordingly slightly fanned inward to bring them into proper co-operation with said levers. It will be perceived that the motion of each of the links 80 is a straight fore and aft sliding motion and that that part of each of said links that passes between two of the sub-levers 31 lies in a straight fore and aft direction. The result is that there is no interference between the sub-levers and the links. It will also be perceived that by the use of the system of rock shafts 66 the tabulator keys 69 may be spaced any desired distance apart without affecting the spacing of the links 80. As shown in the present instance said keys extend only part way across the keyboard, a space being left on the right for the keys 100 of a column jumper (not shown), but it will be obvious that if no column jumper is used the series of keys could be disposed centrally of the keyboard by a slight modification of the length and positioning of the rock shafts.

It will be perceived that the links or push bars 80 have their forward ends nearly directly in front of the levers 45 to which said

links, at their rear ends, are respectively connected so that said links transmit the motion of the arms 78 to said levers by practically a straight line motion. In a machine in which the sub-levers 31 are not used the forward ends of the links could be spaced the same distance apart as their rear ends and then said links would have an absolutely straight line motion. It will thus be seen that the tabulator keys 64 may be spaced any desired distance apart transversely of the machine and the motion of said keys may be transmitted to the tabulator stops, which are grouped closely together near the middle of the machine, by connections having simple rocking and right line motions.

It will be understood that when I refer to the members 66 as rock shafts, I do not mean that they are necessarily round, solid rods, but that sleeves or yoke frames or any of the well known mechanical equivalents of rock shafts may be used instead, or some of said rock members may be of one kind and some of another. So far as I am aware it is broadly new to provide any horizontally and transversely disposed oscillatory members whatever in the relation in which, and for the purpose for which the rock shafts 66 are used in the present construction. It is also new, so far as I am aware, to distribute a series of tabulator keys across the keyboard of a typewriting machine and to transfer and translate the motion of said keys by transversely and horizontally arranged rocking members of any description to a fore-and-aft motion near the middle of the machine and to transfer this motion by fore-and-aft moving members to points near the back of the machine where the tabulator stop mechanism is usually situated.

Various changes in the details of construction and arrangement may be made without departing from my invention.

What I claim as new and desire to secure by Letters Patent, is:—

1. In a typewriting machine and tabulating mechanism, the combination of a carriage; a series of tabulator stops; a frame having a series of slots in its upper side; a series of bars for operating said stops, said bars slidably mounted in said slots; and a series of key operated rock shafts having arms extending into said slots and adapted to operate said bars and to retain them in position in said slots.

2. In a typewriting machine and tabulating mechanism, the combination of a carriage; a series of tabulator stops; a series of key-operated levers; a series of horizontal rock shafts each arranged transversely of the machine and connected to said key operated levers, said rock shafts standing one in front of another; arms on said rock shafts; and connecting bars operated by said arms and operating said stops.

3. In a typewriting machine, and tabulating mechanism, the combination of a carriage; a series of tabulator stops; a series of transverse horizontal rock shafts arranged one in front of another; a series of tabulator key levers of different lengths mounted on said rock shafts and extending to the keyboard of the machine; a series of arms on said rock shafts, said arms being of different lengths appropriate to the respective lengths of the corresponding key levers; and connecting bars operated by said arms and operating said stops.

4. In a typewriting machine and tabulating mechanism, the combination of a carriage; a series of tabulator stops; a series of transverse horizontal rock shafts arranged one in front of another; a series of tabulator key levers of different lengths mounted on said rock shafts and extending into the keyboard of the machine; a series of tabulator keys mounted on said key levers and arranged in a transverse row in the keyboard; a series of arms mounted on said rock shafts; and connections between said arms and said stops; those rock shafts that stand near the front of the machine being at a less elevation than those behind them and the arms on the several rock shafts terminating at substantially the same level, whereby said arms are made of different lengths appropriate to the lengths of the respective key levers.

5. In a typewriting machine and tabulating mechanism, the combination of a carriage; a series of tabulator stops; a series of character key levers and printing instrumentalities operated thereby; a series of depressible tabulator keys arranged in a transverse row at the back of the key board; a series of tabulator key levers extending from said keys toward the back of the machine; a series of transverse horizontal rock shafts on which said tabulator key levers are mounted; a series of arms on said rock shafts; and means including a series of connecting bars connecting said arms with said stops.

6. In a typewriting machine and tabulating mechanism, the combination of a carriage; a series of tabulator stops; a series of tabulator key levers, one for each stop; a series of transverse horizontal rock shafts, each having one of said key levers mounted on one end thereof, and each having an arm mounted thereon at a distance from said key lever; and means whereby said arms operate said stops.

7. In a typewriting machine and tabulating mechanism, the combination of a carriage; a series of tabulator keys; a series of rock shafts lying transversely of the machine and to which said keys are connected; a bracket near the middle of the machine in which each of said rock shafts is journaled at one end; arms on said rock shafts; and means whereby said arms operate said stops.

8. In a typewriting machine and tabulating mechanism, the combination of a carriage; a series of tabulator stops; a series of rock shafts, each journaled at one end near the middle of the machine, said rock shafts extending horizontally from the middle of the machine transversely in both directions; a series of tabulator key levers mounted on said rock shafts; arms on said rock shafts; and means whereby said arms operate said stops.

9. In a typewriting machine and tabulating mechanism, the combination of a carriage; a series of tabulator stops on said carriage; a detachable frame having a bracket situated near the middle of the machine; rock shafts 66, each journaled at one end in said bracket 75, some of said rock shafts being on one side of said bracket and some on the other; tabulator key levers mounted on said rock shafts; and means whereby said rock shafts operate said stops.

10. In a typewriting machine and tabulating mechanism, the combination of a carriage; a series of tabulator keys in the keyboard of the machine; a series of transverse horizontal rock shafts arranged one in front of another and each connected with one of said keys; and tabulator stop devices controlled by said rock shafts for arresting said carriage in different positions.

11. In a typewriting machine and tabulating mechanism, the combination of a carriage; a series of tabulator keys in the keyboard of the machine; a series of rock shafts arranged one in front of another; one of said rock shafts being connected with each of said keys; arms on said rock shafts; connecting bars extending from said arms toward the back of the machine; and means controlled by said connecting bars for arresting said carriage at different positions.

12. In a typewriting machine and tabulating mechanism, the combination of a carriage; a series of character keys; a series of types operated by said character keys; connections between said character keys and said types; said connections including a series of upstanding type actuating members 31; a series of connecting bars extending towards the back of the machine and so spaced apart that each connecting bar passes freely between two consecutive type actuating members 31; a series of transverse horizontal rock shafts having arms, one connected with each of said connecting bars; a series of tabulator keys, each of which is connected with one of said rock shafts; and tabulator stop devices controlled by said connecting bars for arresting said carriage in different positions.

13. In a typewriting machine and tabulating mechanism, the combination of a carriage; a series of tabulator key levers; a series of transverse rock shafts of different

lengths standing one in front of another, the longest of said rock shafts being nearest the back of the machine and each of said rock shafts having one of said key levers mounted thereon; arms on said rock shafts near the middle of the machine; connecting bars operated by said arms; and tabulator stop mechanism operated by said connecting bars.

14. In a typewriting machine and tabulating mechanism, the combination of a carriage; a detachable frame 67 having a series of slots 79 in the upper face thereof; a bracket 75 rising from said frame 67 near the middle of the machine; a series of transverse rock shafts, each journaled at one end in said bracket 75, some of said rock shafts being on one side of said bracket and some on the other; arms on said rock shafts extending into said slots; connecting bars 80 extending towards the back of the machine and lying in said slots; tabulator key levers mounted on said rock shafts; and tabulator stop mechanism operated by said connecting bars.

15. In a typewriting machine and tabulating mechanism, the combination of a carriage; a series of tabulator keys distributed transversely across the keyboard of the machine; a series of transversely disposed rocking members arranged to transfer the motion of said keys to points near the middle of the machine; a series of fore-and-aft moving members near the middle of the machine for transferring the motion of said rocking members towards the back of the machine; and tabulator stop devices operated by said fore-and-aft moving members.

16. In a front-strike typewriting machine and tabulating mechanism, the combination of a carriage; a series of character key levers and front-strike type bars operated thereby; a tabulator key mechanism mounted above said character key levers and below said type bars, said key mechanism comprising a series of key levers distributed transversely of the machine; a series of fore-and-aft moving members near the middle of the machine; a series of oscillatory members connecting said key levers and said fore-and-aft moving members; and tabulator stop mechanism operated by said fore-and-aft moving members.

17. In a front-strike typewriting machine and tabulating mechanism, the combination of a carriage; a series of character key levers and front-strike type bars operated thereby; a tabulator key mechanism mounted above said series of character key levers and below said series of type bars and comprising a series of key levers distributed transversely of the machine, a series of rocking members arranged one in front of another and operated by said key levers, and a series of connecting bars near the middle of the machine, said links operated by said rock-

ing members; and tabulator stop devices operated by said connecting bars.

18. In a typewriting machine and tabulating mechanism, the combination of a carriage; a series of tabulator key levers; a series of transversely disposed oscillatory members off-set from the key levers for transmitting the motion of said tabulator key levers and translating such motion into fore-and-aft motion at a distance transversely of the machine from certain of said key levers; means for transmitting such fore-and-aft motion toward the back of the machine; and tabulator stop mechanism operated by the last mentioned means.

19. In a typewriting machine and tabulating mechanism, the combination of a carriage; a series of tabulator key levers; a series of transversely disposed oscillatory members off-set from the key levers for transmitting the motion of said tabulator key levers and translating such motion into fore-and-aft motion at a distance transversely of the machine from certain of said key levers; means for transmitting such fore-and-aft motion toward the back of the machine; tabulator stop mechanism operated by the last mentioned means; and a carriage release device operated by said key levers.

20. In a typewriting machine and tabulating mechanism, the combination of a carriage; a series of upstanding levers having tabulator stops at their upper ends; a series of connecting bars connected with said levers near their lower ends and extending toward the front of the machine, said connecting bars mounted for substantially straight line fore-and-aft motion; a series of rocking members each disposed transversely of the machine and operating said connecting bars; and a series of tabulator key levers connected with said rocking members.

21. In a typewriting machine and tabulating mechanism, the combination of a carriage; a series of upstanding levers having tabulator stops at their upper ends; a series of connecting bars connected with said levers near their lower ends and extending toward the front of the machine, said connecting bars mounted for substantially straight line fore-and-aft motion; a series of rocking members each disposed transversely of the machine and operating said connecting bars; a series of tabulator key levers connected with said rocking members; a universal bar operated by said upstanding levers; and a carriage release device operated by said universal bar.

22. In a typewriting machine and in tabulator mechanism, the combination with a carriage, of a series of tabulator stops, a series of rock shafts having forwardly extending arms, tabulator keys in the keyboard of the machine connected with said

forwardly extending arms, vertically disposed arms on said rock shafts, and operating connections between said vertically disposed arms and said tabulator stops.

5 23. In a typewriting machine and in tabulator mechanism, the combination with a carriage, of a series of tabulator stops, a series of rock shafts having horizontally disposed key bearing arms of different lengths, 10 tabulator keys in the keyboard of the machine connected with said key bearing arms, vertical arms on the several rock shafts, said vertical arms being of different lengths, and connections between said vertical arms and 15 said tabulator stops.

24. In a typewriting machine and in tabulator mechanism, the combination with a carriage and a series of printing key levers, of a series of tabulator stops, a series of 20 horizontally disposed rock shafts mounted above the printing key levers and having forwardly extending key bearing arms, tabulator keys connected with said arms, vertically disposed arms on said rock shafts arranged close together, and connections between said vertically disposed arms and said 25 tabulator stops.

25. In a typewriting machine and tabulating mechanism, the combination of a carriage, a plurality of closely arranged decimal 30 tabulator stops, a plurality of closely ar-

ranged actuating devices therefor, a plurality of transversely arranged rock shafts of progressively increasing lengths, a plurality of operating devices actuatable by said rock 35 shafts and arranged in different vertical planes longitudinally of the machine so as to coöperate with said plurality of closely arranged actuating devices for the tabulator stops, and a series of comparatively wide- 40 spread key operated levers operatively connected to said rock shafts.

26. In a typewriting machine and tabulating mechanism, the combination of a carriage, a plurality of closely arranged upright decimal stop levers, a plurality of closely arranged horizontal fore and aft actuating bars therefor, a plurality of type- 45 actions comprising a series of upstanding levers which alternate with said horizontal 50 actuating bars where they cross one another, and key operated transverse rock shafts having means for moving said actuating bars.

Signed at the borough of Manhattan, city of New York, in the county of New York, 55 and State of New York, this 19th day of July A. D. 1905.

JACOB FELBEL.
